UNITED STATES PATENT OFFICE.

MARGARET I. SANDES, OF CHICAGO, ILLINOIS.

DESIGN FOR A BADGE.

SPECIFICATION forming part of Design No. 18,745, dated November 20, 1888.

Application filed July 18, 1888. Serial No. 280,338. Term of patent 7 years.

To all whom it may concern:

Be it known that I, MARGARET I. SANDES, a citizen of the United States, residing at Chicago, in the county of Cook and State of Illinois, have invented and produced a new and useful Design for Badges, of which the following is a specification, reference being had to the accompanying drawing, forming part thereof.

10 In the figure I have illustrated by a plan view my newly-designed badge, which consists of the outlines of a Maltese cross with a central circle with the ornaments as herein described. The outer portion of each limb of the cross may be provided with a raised edge, A, and an inner raised portion, B, having ridges or striations (indicated by the letter C) to furnish background for the words and figures. Upon a circle concentric with the cen-

ter of the badge, and in each limb of the cross, 20 may be placed words and letters. The circle D is provided with a row of stars, E E. This circle D may be raised. Within this circle is an annular central field having within the same the monogram of interlaced fanciful 25 ornamentation, as shown and described.

I claim—

The design for a badge, consisting of a Maltese cross with spaces in the limbs thereof for words, letters, or figures, a circle about the 30 base of the limbs with stars thereon, and an annular central field having within the same a monogram of interlaced fanciful ornamentation, as shown and described.

MARGARET I. SANDES.
